UNITED STATES PATENT OFFICE

PEPPINO GIORGIO, OF EAST CHICAGO, INDIANA

DRAFT MOTOR

Application filed November 28, 1931. Serial No. 577,813.

This invention relates to a draft motor.

An object of my invention is the construction of a simple and efficient draft motor whereby a maximum amount of power is procured at a minimum expense.

Another object of my invention is the construction of a motor including a heated flue or stack unit, a branch leading therefrom and a motor unit connected to said branch, all being necessary in producing a highly successful and efficient means for deriving power at a minimum expense.

A still further object of my invention is the construction of an apparatus in which an efficient, heated draft is utilized in conjunction with a motor unit, associated in a novel manner therewith, for obtaining a substantial perpetual operation of the motor unit at practically no expense for maintenance or up-keep, notwithstanding the apparatus will have a long and successful period of operation.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in front elevation of a draft motor constructed in accordance with the present invention.

Figure 2 is an enlarged, vertical, longitudinal, sectional view of the motor unit of the draft motor.

Figure 3 is a front view of the motor unit shown in Fig. 2, while

Figure 4 is a similar view with the control plates removed.

Figure 5 is an enlarged sectional view taken on line 5—5, Figure 2 and looking in the direction of the arrows.

Figure 6 is an enlarged perspective view of the saddle bracket.

Figure 7 is an enlarged fragmentary perspective view of the inner end of the shaft.

Figure 8 is a fragmentary plan view of the propeller.

Figure 9 is a view in side elevation of another embodiment of the draft motor.

Figure 10 is a front view of another embodiment of the draft motor.

Referring to the drawings by numerals, 1 designates the heating unit, 2 is the heated stack unit, 3 is the branch unit and 4 is the motor unit of the draft motor. The heating unit may be of any type of a stove, burner or furnace, whereby it has been found by experience a better draft is created in the stack unit 2.

The motor unit 4 comprises a hollow base 5 which supports the cylindrical casing 6. The upper end of casing 6 is closed by the branch unit 3 which is usually a pipe. On the lower horizontal end of casing 6 is formed two outwardly extending integral bracket plates 7, each provided with vertically extending ears 8. Each ear is provided with an aperture 9 for the purpose hereinafter specified. Movable control plates 10 are placed against the inlet end of casing 6, in engagement with the bracket plates 7. Each control plate (Fig. 3) is provided near opposite edges with elongated slots 11. Bolts 12 extend through the apertures 9 and slots 11, with butterfly nuts 13 thereon, whereby the control plates can be brought together, or separated, and held in their adjusted position, for controlling the amount of air entering casing 6. Each control plate 10 is provided with a grip 14 parallel with and positioned between the pair of ears 15 on said plate. By means of these grips 14, the operator can easily adjust the position of the control plates upon the motor.

In the cylindrical curved casing 6 is placed a saddle bracket 16 which comprises a flat straight body 17 provided at its ends with curved, inwardly and downwardly extending flat legs 18. The flat body 17 is provided with two aligned slots 19, and each leg is provided with a longitudinally extending slot 20. The legs 18 engage the inner curved face of the casing 6 (Fig. 5) and bolts 21 extend through the casing and slots 20, holding the saddle bracket in an adjusted position, but permitting the operator to adjust the bracket, by a sliding action, for assisting in accurately

centering or positioning the horizontal shaft 22. A slideable ball bearing 23 is seated on the flat body 17, with bolts 24 extending therethrough and also through the elongated slots 5 19, whereby the bearing 23 can be bodily adjusted longitudinally of the saddle bracket for further adjustment of shaft 22, to obtain a perfect or extremely accurate positioning of the shaft in the motor. An oil pipe 25, 10 carrying a cup 26, is extended through casing 6 and discharges at its inner end into the bearing 23 for perfectly lubricating the bearing and its shaft 22. Shaft 22 is also journalled in a bearing 27, supported upon 15 the outside of the base 5 (Fig. 2); this shaft 22 is further journalled in bearing 28, on post 29. A balance or fly wheel 30 is mounted on the shaft 22, as well as a belt wheel 31. The belt wheel 31 could be any kind of 20 ordinary means for taking the power from shaft 22 and driving or operating any suitable machinery (not shown).

The propeller 32 is provided with a square aperture 33 (Fig. 8) whereby the propeller 25 fits upon the square portion 34 of the shaft 22 (Fig. 7), and by suitable nuts, the propeller is held in place.

In the embodiment shown in Fig. 9, the 30 motor unit 4 is connected directly to the stack 35. Any suitable means may be used in this embodiment to heat the stack, to greatly increase the draft and thereby the efficient operation of the motor unit.

In the embodiment shown in Fig. 10, the 35 stack 36 has the heating unit 1 connected thereto by a branch 37 with a branch 38 connected at its lower end to the motor unit 4. In Figs. 9 and 10, the motor units 4 preferably rest upon bases 39. In detail construction, the motor unit of embodiments 40 9 and 10 is the same as the motor unit shown in Figs. 1 and 2.

From extensive experience with a draft motor, as herein described, it has been found 45 that heating the stack greatly increases the draft action on the propeller 32, which increases the power derived and consequently the value of the motor. By adjusting the control plates, the size of the inlet end can 50 be increased or decreased, which operates to control the inflowing air against the blades of the propeller. The propeller will continuously revolve as long as there is any draft and consequently, when it is desired to inspect 55 the motor unit, or repair any part thereof, the propeller can be stopped from rotating by raising the vent slide 40, to open the vent opening 41, on stack 2, Fig. 1, which will stop the draft through the casing 6 and thereby the 60 operator can easily stop the propeller when desired. This vent device on the stack (constituted by opening 41 and slide 40) acts as a brake on the motor, when it is desired to stop the propeller and its shaft from rotating. Thorough tests have been given this

draft motor, and the essential units of the combination have been found to produce an apparatus of high efficiency. Further, the inexpensive maintenance of the draft motor is of great importance, since power can be 70 procured at a minimum cost.

While I have described the preferred embodiments of my invention and illustrated the same in the accompanying drawings, certain minor changes or alterations may appear to one skilled in the art to which this invention belongs, during the extensive manufacture of the same, and I, therefore, reserve the right to make such changes or alterations as shall fairly fall within the scope of the appended claims.

What I claim is:

1. In a draft motor, the combination with a stack, of a motor unit communicating with said stack, said motor unit comprising a casing provided on its outer end with a pair of outwardly extending vertically-positioned bracket plates integral therewith, each bracket plate provided with an upwardly and downwardly extending ear formed in the same vertical plane, control plates laid flat against said bracket plates, each control plate provided near opposite ends with elongated slots and with parallel ears, said slots and ears over the ears of said bracket plates, bolts extending through the ears of said bracket plates and the elongated slots of said control plates for securing the control plates in an adjusted position upon said bracket plates, each control plate provided with a grip parallel with and between the ears on said plate, and a shaft provided with a propeller in said casing, substantially as shown and described. 90

2. In a draft motor, the combination with a stack, of a motor unit communicating with said stack, said motor unit comprising a casing, an adjustable saddle bracket mounted in said casing, means on said bracket and casing for holding said bracket in an adjusted position, a slideable ball bearing on said saddle bracket, a ball bearing outside of said casing, a shaft journalled on said ball bearings, and a propeller fixedly secured to said shaft within said casing. 105

3. In a draft motor, the combination with a stack, of a motor unit connected to said stack, said motor unit comprising a cylindrical curved casing, a saddle bracket in said casing, said saddle bracket comprising a flat straight body provided at its ends with downwardly and inwardly extending flat legs, said legs conforming to the shape of and against the curved inner face of said cylindrical casing, said flat straight body provided with aligned elongated slots, each of said legs provided with a longitudinally extending slot, fastening means extending through said casing and said slots of the legs securing the saddle bracket in an adjusted position upon said casing, a slideable ball bearing on said flat 110 120 125 130

body over said aligned elongated slots, fastening means extending through said slideable ball bearing and said slots for securing said ball bearing in an adjusted position on said
5 saddle bracket, a shaft extending into aid casing and journalled in said ball bearing, and a propeller fixedly secured to said shaft within said casing, substantially as shown and described.

10 In testimony whereof I hereunto affix my signature.

PEPPINO GIORGIO.
